VANE PROPELLER

Arthur L. Akre, Vancouver, British Columbia,
Canada

Application September 6, 1949, Serial No. 114,259

12 Claims. (Cl. 170—143)

1

This invention relates to novel vane type propellers and oscillating means for feathering the vanes of said propellers.

Vane type propellers have not been successfully applied to craft, such as boats or aircraft, as propulsion means because of their low efficiency. Considerable of the input power is used up in overcoming the forces that act on the vanes that are not exerting their surfaces in a power thrust against the medium in which the propeller is operating. When a propeller with stationary vanes or paddles, such as a paddle wheel, is observed rotating in water, it will be seen that the blades exert a push for but a small fraction of their rotation. For the balance of the revolution, they are either pushing against, down on or lifting up the medium.

It is the main purpose of this invention to overcome these difficulties. Suitable means is provided for causing each vane to rotate in a planetary manner with respect to the general rotation of the propeller. The means for rotating the vane is designed to maintain the vane substantially at right angles to the medium in which the propeller is operating during the part of each revolution thereof. During the remainder of the revolution the vane is gradually turned to a position which is substantially tangential to the circle described by the propeller. Actually, the vane is doing the most work when it lies radially in relation to the propeller circle, and it gradually turns from this position to a tangential position and then back to the radial position. It has been found helpful if the main body of each vane is made of a flexible material so that the vane will exert the maximum amount of pressure against the medium when it is in its working position, and a minimum amount of friction when it is out of said position.

One of the advantages of this invention lies in the fact that a propeller may be constructed for boats generally. The mechanism for rotating each vane is designed for a particular purpose, that is, for heavy duty, speed, or relatively slow operation. The same applies to propellers to be used on aircraft.

The present propeller may incorporate means for automatically adjusting the vanes within a limited degree to suit varying load and speed conditions.

Examples of this invention are illustrated in the accompanying drawings, in which:

Figure 1 is an elevation of one type of propeller.
Figure 2 is a side elevation of control mechanism for controlling the vane of this propeller.

2

Figure 3 is an enlarged section taken on the line 3—3 of Figure 1.

Figure 4 is an enlarged detail of an alternative form of propeller.

5 Figure 5 is an elevation similar to Figure 1 of yet another form of invention.

Figure 6 diagrammatically illustrates the grooving of a vane control gear used in the propeller of Figure 5.

10 Figure 7 diagrammatically illustrates the various positions of each vane of a propeller as the latter rotates.

Figure 8 is a reduced side elevation of the propeller.

15 Figure 9 is a section through an alternative form of driving connection for the propeller vane.

Figure 10 is a section taken on the line 10—10 of Figure 9.

20 Figure 11 is a section taken on the line 11—11 of Figure 9.

Figure 12 is an enlarged longitudinal section taken on the line 12—12 of Figure 1, and

25 Figure 13 is an enlarged detail of the alternative of Figure 4.

Referring to Figures 1 to 3, the propeller is mounted on a craft, such as a boat or aircraft, in any convenient manner and at any desired point. In this example, the propeller is carried by a pair of supports 10 which are secured to the

30 craft, not shown, in a convenient way. The propeller consists of a pair of spaced hollow arms 11 and 12 having hubs 13 and 14 at their inner ends which are rotatably carried by the supports 10, as shown. The inner ends of these arms are connected by a tube 15. Another pair of arms 16 and 17 project outwardly from the hubs 13 and 14 diametrically opposite the arms 11 and 12. In this example, the arms 16 and 17 carry a counter-weight 18 adjacent their outer ends.

35 A vane 20 has shafts 21 and 22 projecting outwardly from opposite sides thereof midway between its opposite ends. These shafts are journaled in the arms 11 and 12, respectively, adjacent their outer ends and have bevel gears 23 and 24 mounted thereon within said arms. These gears mesh with bevel gears 25 and 26 which are mounted on shafts 27 and 28 extending longitudinally of their respective arms, having bevel gears 29 and 30 on their inner ends adjacent the hubs 13 and 14. A shaft 34 extends through the arms 11 and 12, tube 15 and through the hub 13 centrally of the latter, and gears 35 and 36 mounted thereon mesh with the gears 29 and 30.

40 The vane 20 may be formed of solid material,

but it is preferably formed of a flexible material, such as canvas. In the latter case, the vane consists of a flexible body 20a having edges 20b which are connected to side supports 20c from which the shafts 20 and 21 project.

The propeller is rotated in any suitable manner. For example, the propeller illustrated in Figure 1 is provided with a gear or sprocket 38 mounted on the hub 14, and this gear or sprocket is suitably connected to a source of power, not shown, in the craft. If desired, a similar gear or sprocket may be mounted on the hub 13.

The propeller is rotated by means of the gear or sprocket 38, and the vane 20 moves around the centre of the propeller, which is represented by the hubs 13 and 14. At the same time, the vane rotates around its own axis which coincides with shafts 21 and 22. The angle of the vane in relation to the arms of the propeller at any desired point during rotation of the latter may be changed by rotating the shaft 34 which, in turn, rotates the shafts 27 and 28 to turn the vane shafts 21 and 22.

An automatic control is provided for changing the angle or setting of the vane 20 during rotation of the propeller. A hollow shaft 40 is fixedly connected to the hub 13 and projects into a control box 41 which is pivotally mounted on said shaft. The shaft 34 extends through the shaft 40, and through and beyond the box 41. A gear 42 mounted on the shaft 40, meshes with a gear 43 mounted on a shaft 44 extending transversely of the control box. The latter shaft extends outside the box and has a crank 45 fixedly mounted thereon. This crank is connected by a link 47 to a lever 48 which is fixed to a shaft 49 also extending transversely of the box. An adjusting link 52 is fixedly mounted adjacent one end on the shaft 49 and extends outwardly beyond the control box. This link has an arcuate slot 53 extending substantially longitudinally thereof. A connecting arm 54 has at one end a pin 55 riding in the slot 53, and is pivotally connected at its opposite end to a lever 56 which is fixed to and projects outwardly from a transverse shaft 57 in the same direction as the link 52. The latter shaft lies substantially parallel with the shafts 34, 44 and 49, and projects outwardly from the box and has a gear 58 mounted thereon, which meshes with a gear 59 mounted on the shaft 34 in line therewith.

Suitable means is provided for shifting the arm 54 longitudinally of the adjusting link 52. This may be accomplished by a support 62 which is pivotally connected to the arm at 63, and extends towards and through the box. The support 62 is provided with a portion 64 extending substantially at right angles thereto hingedly connected to the box at 65. An adjusting screw 67, see Figure 3, is threaded through a lug 68 carried by the side of the box 41, extends freely through the portion 64 of the support 62, and has a suitable bearing 65a mounted on this end, upon which the portion 64 rests. Thus, the adjusting screw 67 may be turned in either direction to move the arm 54 and, consequently, its pin 55 in either direction along the slot 53.

When the propeller is rotated, gear 42 turns gear 43, and the latter rotates the cam 45. This cam reciprocates the lever 48 through the link 47 and causes the adjusting link 52 to oscillate. The latter movement is transferred to the lever 56 through the arm 54. This lever turns the gear 59 back and forth, and the motion is transferred through the shafts 34, 27 and 28, and 21

and 22 to the vane 20. The degree of this turning or oscillating motion of the vane depends upon the setting of the arm 54 in relation to the adjusting link 52. The oscillating motion becomes less or greater as the pin 55 is moved respectively towards or away from the pivot shaft 49 of the link.

The position of the vane in relation to the arms 11 and 12 at any point during a revolution of the propeller, may be changed by swinging the control box 41 around the shaft 40. This moves the gear 43 around the gear 42. If desired, the control rod 69 may be connected to one end of the control box at 70, the opposite end of said rod extending into the craft.

In Figure 7, the circle 75 represents the path described by the shafts 21 and 22 of the vane 20. The position of the latter is shown at various points on this circle. Arrow A shows the direction of rotation of the propeller and arrow B the direction of movement of the craft. When the vane is at the bottom of the circle 75 and on the vertical centre line thereof, it lies substantially at right angles to the direction of movement of the craft. As it moves through the next quadrant of a circle, its angle changes very little in relation to the arrow B. However, in the next quadrant, the vane turns rapidly until it lies substantially parallel of the arrow B at the top of the circle. It is now tangential in relation to the circle. In the third quadrant, the angle changes little so that the vane remains substantially tangential to the circle. At the beginning of the fourth quadrant, the vane is almost at right angles to the arrow B so that, as the vane moves through this quadrant, it turns very little. At the end of this quadrant or at the bottom of the circle, the vane lies at right angles to the arrow B. Thus, in the quadrants below the horizontal centre line of the circle, the vane lies substantially at right angles to the arrow B, while above the horizontal centre line it assumes a position substantially tangential to the circle.

It will be noted that in the fourth quadrant, the flexible body 20a of the vane is bellied out behind the supports 20c. However, in the first quadrant, the body bellies out on the opposite side of the supports. This is caused by the medium in which the propeller is operating. The medium at this point is moving in the direction opposite to arrow B faster than the vane. This results in the body offering less resistance to the medium in the second and third quadrants. As the vane turns completely over in these quadrants, the body is behind the supports relative to their movement, in the third and fourth quadrants.

Figure 4 is an enlarged view, partly in section, of one end of an adjustable type of vane. In this form of the invention, the shafts 22 and 28 of the arm 12 and the vane, respectively, are hollow. A shaft 80 extends through the shaft 28 and has a bevel gear 81 on its end which meshes with a bevel gear 82 mounted on a shaft 83 extending through the shaft 22, said shaft 83 having a small bevel gear 84 on its inner end.

The vane itself is formed with a body of a suitable flexible material 87, such as heavy canvas, and has edges 88 and 89 formed of a light and stiff material, such as metal. A hollow supporting member 90 is provided at each side of the vane and the material 87 is adjustably connected thereto. The shaft 22 projects outwardly from this member midway between the ends

thereof into the arm 12 of the propeller. In this example, a link 91 is connected to each corner of the vane and extends through an elongated slot 92 in the member 90 adjacent its outer end.

A turnbuckle 94 is mounted in the member 90 at the centre thereof, and the sleeve 95 of this turnbuckle has a bevel gear 96 thereon which meshes with the gear 84 on the shaft 83. Screws 97 and 98 project outwardly from the opposite ends of the sleeve 95. A flexible cable 100 is connected to the outer end of the screw 97, is looped around a pulley 101 and extends around another pulley 102 of the outer end of the member 90. This cable continues and is connected to the outer end of the screw 98 at 103. Similarly, a cable 106 is connected to the outer end of the screw 98, is looped around a pulley 107, and extends around another pulley 108 at the opposite end of the member. This cable extends to and is connected to the screw 97 at 109. The links 91 are connected to the cables 100 and 106 between the pulleys 101 and 102, and 107 and 108, respectively. A stay 112 is secured to the material 87 adjacent each side thereof parallel with the arm 90. A cable 113 extends from this stay into the arm 90 around a small pulley 114 and is connected to the outer end of the screw 97. Another cable 115 is connected to said stay and extends into the member around a small pulley 116 and is connected to the screw 98.

Suitable mechanism extends from the rod 80 into the craft so that said rod may be turned by a person in the craft. Figure 13 illustrates one way of doing this. The lower end of rod 80 has a bevel gear 165 thereon meshing with a bevel gear 166 mounted on a shaft 167 extending through hub 14 and support 10. A gear or sprocket 168 is mounted on the outer end of the shaft. Suitable turning means, not shown, extends from the gear 168 into the craft in order that said gear may be rotated to turn rod 80. When this rod is turned in one direction, the screws 97 and 98 move out of the sleeve 95 of the turnbuckle. The screw 98 pulls the cable 100 so that the link 91 attached thereto is moved towards the end of the member 90. Similarly, the screw 97 pulls the cable 106 to move the link 91 connected thereto towards its end of the member. This action stretches or flattens the material 87. When the rod 80 is turned in the opposite direction, the turnbuckle operates in the opposite manner and the cables 101 and 106 are pulled to move the links 91 of each member 90 towards each other. This slackens the material 87 and allows it to belly out.

Figure 5 shows a propeller having two vanes 20, one at the ends of the arms 11 and 12 and the other at the ends of the arms 16 and 17. In this example, the mechanism for adjusting the angle of the vanes 20 in relation to the propeller as the latter rotates is different from that illustrated in Figures 1 and 2. A shaft 120 extends through the arms 11 and 12, tube 15 and through the hub 13 beyond the adjacent support 10. A link 121 is connected to this end of the shaft by means of which the latter may be rotated. A special control gear 124 is mounted on the shaft 120 of each of the arms 11 and 12. The mechanism in both these arms is the same, and as the arm 12 has been shown in section, the mechanism in that arm will now be described in detail. Each gear has on one face thereof a plurality of spaced teeth 125 forming tracks 126 therebetween, see Figure 6. The teeth and tracks spiral out from the centre to the edge of the

gear. It will be noted that the teeth and tracks are of different lengths. A pinion gear 128 is mounted adjacent and in engagement with the gear 124 at each of two opposite sides thereof. Each pinion has teeth 129 shaped to mesh with the tracks 126 of the gear.

One or more of the teeth 129 are always in mesh with one or more of the tracks 126 of the control gear. A shaft 131 extends outwardly from each pinion 128 and has a bevel gear 132 on its outer end meshing with another bevel gear 133 mounted on the shaft 22 of the vane which extends into the arm 12 or 17, as the case may be.

When the propeller is rotated, the pinions 128 at each side thereof move around the adjacent control gears 124. As the teeth 129 are meshing with the tracks of the gear, the pinions are rotated during this time. This rotation swings the vanes 20 around their shafts 21 and 22. If the pinion teeth are moving in the longer tracks of the control gears, the turning movement of the vane is fairly slow relative to the rotation of the propeller. When the said teeth are moving along the shorter tracks, the turning movement on the vane is much faster. Suitable connecting means extend from the link 121 into the craft so that the shaft 120 may be turned from within the latter. This turns the control gears 124 to change the position of the long and short tracks thereof in relation to the propeller. This changes the point during each revolution of the propeller where the vanes turn rapidly and slowly.

Referring again to Figure 7, it is obvious that each propeller vane is working only when it is near the bottom of a circular path along which it travels. The rest of the time it is merely moving around to a position where it can start again to work. It is the main purpose of this invention to move the vane through the non-operative portion of its travel with the least possible amount of friction or resistance to the medium in which the propeller is operating. Thus, at some points on the circle, it is desirable rapidly to move the vane around its own axis, while at other points slow movement is required. The position where the rapid and slow movements take place and the speed of the movement determines the degree of pull of the propeller. For example, when the propeller is trying to get its load into motion, each vane would work for only a small part along its circular path and would slip with the least amount of resistance possible along the remainder thereof. It is obvious that the vane is doing a maximum amount of work when it is at the bottom of the circle on the vertical centre line, as shown at D in Figure 7. When a lot of slippage is desired, it is necessary to rotate the vane as quickly as possible after it has passed this point into a slipping position. On the other hand, as the vane approaches the vertical centre line at the bottom of the circle, under these circumstances, it is desirable to rotate it as rapidly as possible from the slipping to the working position. As the load gets underway and the strain on the propeller becomes less, its working arc may be increased in order to obtain a maximum effort from the power available.

The gears 124 control the planetary rotation of the vane. The spiral teeth 125 of the tracks 126 are designed for a particular job, thus when a propeller is being installed on say, for example, a boat, the control gears are selected to give the required results. These depend upon the

speed and power required for the particular boat on which the propeller is being installed.

Figures 9, 10 and 11 illustrate an alternative form of pinion gear to be used with the control gears. In this alternative, a disc 140 is fixedly secured to the shaft 131 at the end thereof adjacent a control gear 124. This disc has two arcuate slots 141 formed in its inner surface on opposite sides of the centre thereof, said slots being concentric with the shaft 131. A sleeve 142 is normally retained centrally of each slot by springs 143 and 144 in said slots. A pinion gear 147 similar to a pinion gear 128 is rotatably mounted either directly on the shaft 131 or, as shown, on a sleeve 148, projecting outwardly from the disc 140. This pinion is held in place in any suitable manner, such as by means of a nut 149 threaded on the shaft. This pinion has diametrically opposed pins 151 projecting outwardly from the face thereof bearing against the disc 140. These pins fit into the sleeves 142 of the disc 140.

The teeth of the pinion 147 mesh with the spiral teeth of a control gear 124 in the same manner as the teeth of the pinions 128. The pins 151, sleeves 142, and springs 143 form a resilient driving connection between the pinion and the disc 140, the latter turning the shaft 131 to rotate a vane of the propeller. The springs are strong enough so that when the propeller is turning comparatively slowly or is under normal load, there is no relative movement between the pinion and the disc. However, when the propeller is rotating very fast, it is desirable not to turn the vane as rapidly as when the propeller is turning at a slower speed. Under these circumstances, the control gear may turn the pinion 147 rapidly, but the springs 143 give sufficiently to prevent the vane from being turned as rapidly as the pinion. In fact, the vane may not turn as far as it would without this type of drive.

When the propeller is subjected to an excessive load, it is desirable to shorten the working period of the vane. This is done automatically by this driving connection. When the propeller is rotating, the period of drive of the vane is determined by the speed with which it turns from a slipping to a driving position, the slower the turn, the shorter the driving period. Under excess load, the springs 143 give, thus slowing down the speed of rotation of the vane and automatically shortening the drive period. As the load on the propeller eases up, the give of the springs 143 will grow less until it disappears entirely.

What I claim as my invention is:

1. A vane type propeller comprising supporting means adapted to rotate around a central axis, a vane pivotally mounted substantially midway between its ends on the supporting means on an axis spaced from the central axis, said vane including a flexible body secured at the opposite ends of the vane and adapted to belly out on either side of the plane of the latter, and means including gear means connected to the vane for imparting a planetary motion to the vane about its axis during rotation of the supporting means, the flexible body of the vane bellying out from one side of the plane thereof during part of its revolution and from the opposite side during the remainder of the revolution.

2. A vane type propeller as claimed in claim 1 in which the flexible body is connected at each end to an edge of relatively stiff material extending transversely of the vane.

3. A vane type propeller as claimed in claim 1 in which the vane includes a pair of spaced parallel supports, the flexible body being connected to said supports adjacent the ends thereof.

4. A vane type propeller as claimed in claim 1 in which the vane includes a pair of spaced parallel supports between which the flexible body is positioned, and an edge of stiff material at each end of the body, said edges being connected to the supports adjacent the ends thereof.

5. A vane type propeller as claimed in claim 1 including means on the vane and connected to the flexible body for tightening and slackening the latter to adjust the degree of belly thereof.

6. A vane type propeller as claimed in claim 1 including means carried by the supporting means and connected to the gear means for changing the speed of rotation of the vane at predetermined points as it moves around the central axis.

7. A vane type propeller as claimed in claim 6 including means carried by the supporting means and connected to the speed changing means for selectively changing the predetermined points around the central axis during rotation of the supporting means.

8. A vane type propeller as claimed in claim 1 in which the gear means for imparting a planetary motion to the vane comprises a control gear on the central axis, means normally holding the control gear against rotation, a plurality of teeth on a face of the gear forming tracks therebetween and spiralling from the centre to the edge thereof, a pinion gear mounted on the supporting means adjacent the control gear and having teeth meshing with the teeth of the control gear, said pinion moving around the control gear when the supporting means is rotating, and means connecting the pinion to the vane to cause the latter to rotate when the pinion turns.

9. A vane type propeller as claimed in claim 8 in which some of the teeth and tracks of the control gear are longer than others.

10. A vane type propeller as claimed in claim 8 in which the teeth and tracks in the control gear start at one point and increase in length around said gear to another point and then decrease in length around to the first point.

11. A vane type propeller as claimed in claim 8 including resilient means in the connecting means to allow a degree of relative movement between the vane and the pinion.

12. A vane type propeller as claimed in claim 8 including means operable from outside the propeller for turning the control gear about the central axis to different positions.

ARTHUR L. AKRE.
